DESIGN FOR A COMBINED FISHING REEL AND ROD SEAT

Edwin P. Hurd, Detroit, Mich., assignor to Hurd
Lock & Manufacturing Company, a corpora-
tion of Michigan

Application November 3, 1945, Serial No. 123,434

Term of patent 14 years

(Cl. D31—4)

To all whom it may concern:

Be it known that I, Edwin P. Hurd, a citizen
of the United States, residing at Detroit, Wayne
County, Michigan, have invented a new, original,
and ornamental Design for a Combined Fishing
Reel and Rod Seat, of which the following is a
specification, reference being had to the accom-
panying drawing, forming a part thereof, in
which:

Fig. 1 is a top plan view of a combined fishing
reel and rod seat, showing my new design;

Figs. 2 and 3 are side elevational views and

Fig. 4 is an end elevation of the combined fish-
ing reel and rod seat shown in Fig. 1.

I claim:

The ornamental design for a combined fishing
reel and rod seat, as shown.

EDWIN P. HURD.
